7 Claims. (Cl. 18—16.5)

ABSTRACT OF THE DISCLOSURE

The disclosure of the invention comprises a high pressure press assembly having, in combination, a pair of opposed anvil elements,

each comprising a cylindrical base of large cross sectional area for supporting a maximum axially directed load imposed on said high pressure press assembly, and

adjacent said base converging surfaces terminating in a specimen engaging work face of relatively smaller area concentrating said axially directed load therein, a support cylinder having an internal cylindrical wall extending between and overlying each of said cylindrical bases,

fluid pressure containing seals between said internal cylindrical wall and each of said cylindrical bases, providing with said support cylinder and anvil elements a pressure fluid containing enclosure, means for subjecting said anvil elements to an axially directed compression pressure, and

means directing fluid under pressure into said fluid pressure containing enclosure providing an environmental pressure against any included specimen and exposed surface of said anvil elements between said seals including said converging surfaces and specimen engaging work faces, including means for controlling the fluid pressure within said enclosure to establish a desired relationship of said environmental fluid pressure to axial thrust which is independent of volumetric variation of said enclosure.

A layer of plastic material may overlie said specimen between the anvil elements for protection from said pressure fluid. The specimen may be engaged by a supporting ring of high tensile strength with a sealing ring between the ring and each adjacent anvil element. The construction may also include an anvil tip of transparent material and a supporting anvil base formed with a visual inspection channel therein.

The present invention relates to improvements in high pressure apparatus and more particularly to a high pressure press of the general type opposed anvils acting along a single axis.

High pressure apparatus of the general type having opposed anvils with tip portions of reduced area for engaging a specimen therebetween, wherein said tip portions are externally formed to support maximum pressures within the confines of the opposed anvil surfaces, and in which the specimen may be further supported against lateral expansion and rupture by means of additional fixed and movable metallic reinforcing elements are well known in the art.

The pressure which may usefully be applied with apparatus of this description is limited, however, by the strength of the anvils, particularly the formed portions thereof adjacent the anvil contact surfaces which are of reduced cross section and in which are concentrated the greatest forces tending to rupture and disintegration.

It is an object of the invention to provide a high pressure apparatus of the general type in which a specimen is subjected to a very heavy pressure along one axis be-

2

tween two opposed anvil elements in which there is provided a novel and more efficient means for supporting the specimen and anvils engaging therewith which will very substantially increase the resistance of these elements to rupture as a result of stresses set up by such axially directed pressures.

With the above and other objects in view as may hereinafter appear a feature of the invention consists in the provision of an anvil structure comprising a pair of opposed anvil elements each having a cylindrical base of large cross sectional area for supporting a maximum axially directed load imposed upon said high pressure press assembly, and adjacent said base converging surfaces terminating in a specimen engaging work face of relatively smaller area concentrating said axially directed thrust therein. A support cylinder having an internal cylindrical wall extends between and overlies the cylindrical base portions of said anvil elements. Fluid containing seals disposed between said internal cylindrical wall and each of said cylindrical bases provides with said support cylinder and anvil elements a pressure fluid containing enclosure. Said structure is provided in combination with means directing a pressure fluid into said enclosure so that an environmental pressure is exerted upon the included specimen and upon the included surfaces of the anvils including the anvil work faces and adjacent diverging surfaces of the anvil tip to very substantially increase the amount of the axially directed pressure which can be applied to said press assembly without risk of rupture or disintegration of the anvils and specimen.

An essential feature of the invention consists in the provision of means for controlling said environmental pressure particularly as the opposed anvil elements are moved toward one another for axially loading said high pressure apparatus.

A feature of the invention consists, also, in the method carried out with the apparatus described for subjecting a specimen to high pressures along a single press axis.

The several features of the invention will be readily understood by one skilled in the art from the following description taken in connection with the accompanying drawing in which:

FIG. 1 is a sectional view in side elevation of a high pressure apparatus embodying in a preferred form from the several features of the invention, said apparatus being adapted to be inserted between the platens of a conventional press;

FIG. 2 is a plan view but on a reduced scale of the high pressure apparatus of FIG. 1;

FIG. 3 is a somewhat fragmentary sectional view in side elevation of the high pressure apparatus shown in FIG. 1 set up for operation upon a very thin sample sealed from contact with the surrounding high pressure supporting fluid by means of an O-ring;

FIG. 4 is a fragmentary view of the high pressure apparatus illustrated in FIG. 1 but on a smaller scale set up for operation upon a relatively long sample protected by a rubber jacket, the spherical anvil tips being composed of glass;

FIG. 5 is a sectional view of the high pressure apparatus shown in FIG. 1, in which the sample is further supported laterally by means of a tapered metallic ring of high tensile strength, a pair of O-rings being provided to protect the sample from contact with the surrounding high pressure supporting fluid; and

FIG. 6 is an enlarged fragmentary view of the O-ring and its supporting taper ring by means of which the environmental pressure is caused to act only against outer portions of the tapered support ring for the specimen.

In carrying out the invention opposed anvil assemblies of the general type having massive anvil supports and

anvil contact surfaces of smaller area to obtain a maximum increase in the pressure exerted against an interposed specimen are employed. The massive anvil supports are fitted into opposite ends of a thick walled sleeve element with high pressure packings forming a pressure vessel adapted to contain very high pressures. While the exposed surface portions of the anvils adjacent the smaller contact surfaces in which is concentrated the heaviest load are preferably tapered or spherical in shape to provide exposed surface contours of maximum strength, it will be understood that anvils of other shape may be employed.

A suitable fluid pressure medium, for example oil, is introduced into the pressure chamber bounded by said sleeve element, the massive anvil supports and high pressure packings above described. The pressure fluid introduced into the pressure chamber under very high pressure exerts an enveloping pressure upon the specimen and exposed anvil elements which very substantially increases the resistance of the specimen and anvils to rupture and disintegration induced by very high pressures exerted along the thrust axis of the anvils. Provision is made for continuously adjusting the enveloping fluid pressure within the pressure chamber to maintain said fluid pressure at a desired value as the anvil assemblies are moved toward one another tending to further compress the contained volume of the fluid pressure medium.

Referring more specifically to the drawing my improved high pressure apparatus comprises a pair of opposed anvil assemblies of which the upper assembly comprises a spherical anvil member 10 mounted on a massive anvil supporting element 12 of substantially larger diameter than the spherical anvil member 10, and provided at its outer end with a still larger cylindrical base 14. The lower anvil assembly similarly comprises a spherical anvil member 16 supported on a massive cylindrically shaped anvil support 18 of substantially greater diameter than the spherical anvil member 16 and provided at its lower end with a base 20 of still greater diameter. The two anvil assemblies are supported and are relatively movable toward and away from each other within a very thick walled sleeve 22, which may be made of highly stressed steel, the inner diameter of which is gauged to receive respectively the massive anvil supports 12 and 18. The sleeve member 22 together with the anvil supports 12 and 18 provide a closed pressure chamber 24 within which are mounted the anvils 10 and 16 and the specimen to be supported between the two anvils.

A high pressure friction packing 26 is interposed between the internal periphery of the sleeve 22 and the engaging peripheral surface of the anvil support member 12. A similar type pressure friction packing 28 is provided between the internal peripheral surface of the sleeve 22 and the engaging peripheral surface of the anvil support member 18.

A band 30 of soft steel surrounds the cylinder 22, acting as a safety device to confine the parts in the event that the cylinder 22 should break down under the high internal pressures to which it is subjected.

The high pressure apparatus above described comprising the upper and lower anvil assemblies and the supporting sleeve 22 are adapted to be placed between the two platens 32 and 34 of a conventional press by means of which the anvil assemblies including anvils 10 and 16 are forced toward one another under any desired pressure.

In the illustrated construction means are provided for introducing fluid under pressure into the chamber 24 for externally supporting the anvils 10 and 16 and the specimen to be located therebetween. The fluid medium will preferably be a liquid such as oil, or glycerin and water, or alternatively a gas depending upon the requirements of the particular test or manufacturing operation being carried out. The fluid medium is introduced from any convenient source, not shown, through an inlet conduit 36 and pump 38, from which the fluid is passed through a pressure-regulated valve 40 and a radial inlet conduit 42

4
in the wall of cylinder 22 into the compression chamber 24.

It will be understood that the pressure apparatus above described may be set up for operation upon specimens which may be of many different shapes and sizes or may be composed of materials having widely varying physical characteristics. FIGS. 3, 4, and 5, illustrate three different ways of supporting specimens within the high pressure apparatus disclosed. In FIG. 4 there is a specimen 44 cylindrical in shape and of relatively greater height than diameter which is positioned between the two anvils 10 and 16 which in this instance are made of a transparent material shown as glass and is protected from contact with the pressure fluid within the chamber 24 by means of a rubber or other plastically conforming sheet or jacket 46.

FIG. 3 illustrates an arrangement for applying pressure to a very thin sample 50. As shown, the sample is supported between the anvils 10 and 16 and is protected from direct engagement with the environmental high pressure fluid in chamber 24 by means of an O-ring 52. This is a typical arrangement of a very thin specimen which is capable of withstanding a maximum pressure before excessive deformation and rupture of the specimen takes place.

FIG. 5 illustrates a still different way of supporting a sample 54 in my high pressure apparatus. In this instance a sample 54 mounted between the anvils 10 and 16 is laterally supported by means of an inwardly tapered metallic ring 56 further reinforced about its outer periphery by means of a stressed steel band 58. Two O-rings 60 and 62 are inserted respectively between the supporting band 56 and anvil 10 and between the supporting band 56 and anvil 16 to protect the sample 54 from direct contact with the high pressure fluid. The O-rings 60 and 62 are backed by tapered support rings of which one is shown at 64 in the enlarged detail sectional view FIG. 6. The rings 64 are preferably made of brass or other suitable material which will flow to the extent necessary when subjected to the compressive pressure of the relatively advancing anvil assemblies. The environmental support of the specimen is thus provided by the stressed ring 56 backed by the environmental pressure in the chamber 24 further amplified by the taper of the ring 56. The support provided by the environmental pressure serves also to greatly increase the effective strength of the ring assembly 56, 58.

In operation the apparatus is assembled with a specimen which may, for example, be the very thin specimen 50 of FIG. 3, and the O-ring 52. The assembled high pressure apparatus is placed between the platens 32 and 34 of the press, and an initial thrust may be applied to establish positive contact between the anvils and the specimen and to establish a seal between the anvils and the O-ring. A suitable fluid pressure medium is introduced into the pressure chamber 24 thus producing an enveloping pressure against the exposed spherical surfaces of the anvils 10 and 16, the end faces of the massive anvil supports 12 and 18, and against the edges of the specimen 50. The environmental pressure produced by the fluid pressure medium is increased to a point at which said environmental pressure will prevent plastic deformation, and the subsequent rupture of the anvils and specimen under the extreme pressures to which they are now subjected along the longitudinal axis by the compressive movement of the platens 32 and 34. At all times sufficient thrust must be applied at the platens to oppose and somewhat exceed the thrust resulting from the environmental pressure. The force exerted at the platens has two components: that which is required to resist the environmental pressure, and that which produces the experimental pressure in the specimen.

During the compressive movement of the two anvil assemblies the environmental area 24 occupied by the fluid pressure medium becomes progressively smaller. The environmental pressure is maintained at the desired value during said compressive movements by manipulation of the regulating valve 40.

It is assumed that the anvil supports 12 and 18 are of hard steel, the spherical anvils 10 and 16 are of a material particularly suited to the specimen and the nature of the experiment as sapphire, steel, metal carbide or other essentially hard substance, and the cylinder 22 is of stressed steel, and that the specimen 50 is to be subjected to an axial pressure in the order of one to several million pounds per square inch.

Anvil assemblies of the general type described operating at atmospheric pressure have been found to withstand axially directed pressures in the order of 1,500,000 pounds per square inch. However, when an environmental fluid pressure is introduced into the chamber 24 and is exerted upon all the exposed surfaces of the anvils 10 and 16 and adjacent exposed end faces of the massive anvil supports 12 and 18, the ability of the anvil assemblies to withstand the axial pressure imposed thereon is greatly increased. Depending upon the amount of environmental pressure employed it is assumed that the axial pressure upon the apparatus may be safely stepped up by a factor of 1.5 to 2.5 times. When a suitable high pressure fluid is introduced into the chamber 24 at a pressure in the order of 200,000 pounds per square inch the exposed surfaces of the anvil assemblies and sample will be amply supported against plastic deformation in the presence of pressures exerted axially through the anvil assemblies sufficient to produce the desired one to several million pounds per square inch upon the sample 50 while maintaining a reasonable margin of safety against rupture and disintegration of the apparatus.

While any improved high pressure apparatus above described is particularly adapted for subjecting specimens to very high pressures, the apparatus may be employed with advantage also under different sets of operating conditions which may involve the use of different materials, the application of lower pressures and the like. As an example, anvils of glass or quartz which are brittle and easily fractured may be employed in order to make possible the visual inspection of a specimen while under pressure. Anvils composed of such extremely brittle and easily fractured materials can be subjected to substantially higher axial pressures while supported by applicant's environmental pressure than would normally be considered practicable without risk of fracture or disintegration of the anvils. Visual inspection channels are provided to the glass anvil tips 10a and 16a through central bore 68 and cross groove 70 in anvil supporting element 12 and central bore 72 and cross groove 74 in anvil supporting element 18. The electrical contact plates 76 and spring 78 illustrated for obtaining electrical measurements are removed for this purpose. The high pressure apparatus disclosed is further constructed and arranged to operate with a minimum of those expensive and hard-to-evaluate friction losses which are normally to be expected of a pressure device having moving parts subjected to pressure from different directions. The only friction loss resulting from the application of environmental pressure in the chamber 24 will be the relatively minor friction loss generated in the pressure seals 26 and 28 between the cylinder 22 and the anvil supports 12 and 18.

From the foregoing description it will be appreciated that my improved high pressure apparatus provides a simple structure which is both versatile and highly efficient in operation and capable of operating at ultra high pressures.

The invention having been described what is claimed is:

1. A high pressure press assembly having, in combination a pair of opposed anvil elements each comprising a

cylindrical base of large cross sectional area for supporting a maximum axially directed load imposed upon said high pressure press assembly, and adjacent said base converging surfaces terminating in a specimen engaging work face of relatively smaller area concentrating said axially directed load therein, a support cylinder having an internal cylindrical wall extending between and overlying each of said cylindrical bases, fluid pressure containing seals between said internal cylindrical wall and each of said cylindrical bases, providing with said support cylinder and anvil elements a pressure fluid containing enclosure, means for subjecting said anvil elements to an axially directed compressive pressure, and means directing fluid under pressure into said fluid pressure containing enclosure providing an environmental pressure of less thrust than that exerted by said axial pressure against any included specimen and exposed surfaces of said anvil elements between said seals including said converging surfaces and specimen engaging work faces.

2. A high pressure press assembly according to claim 1 in which means are provided for controlling the fluid pressure within said enclosure to establish a desired relationship of said environmental fluid pressure to axial thrust which is independent of volumetric variation of said enclosure.

3. A high pressure press assembly according to claim 2 in which a layer of plastic material overlies a said specimen between said anvil elements for protection from said pressure fluid.

4. A high pressure press assembly according to claim 2 in which a supporting ring of high tensile strength externally fitted to a said specimen of cylindrical shape between said anvil elements provides support for said specimen radially of said axis, said ring having an internal tubular surface engaging a said sample, a peripheral surface subject to said environmental pressure, and side surfaces formed with radially diverging tapers, and a sealing ring between each said side surface and an adjacent anvil element.

5. A high pressure press assembly according to claim 2 in which the anvil elements comprise a cylindrical base of large diameter, a spherically shaped anvil tip of a smaller diameter having a flat specimen engaging work face concentrating said axially directed load therein.

6. A high pressure press assembly according to claim 2 in which at least one said anvil element is formed with an anvil tip composed of a transparent material having a specimen engaging surface of small area, and adjacent contoured surfaces connecting with said cylindrical base of large cross sectional area, and in which the supporting anvil base for said anvil tip is formed with a visual inspection channel connected between the exterior of said press assembly and said transparent anvil tip.

7. A high pressure press assembly according to claim 2 in which a supporting ring of high tensile strength is fitted to a said specimen between said anvil elements for supporting said specimen, radially of said axis, said supporting ring being located within said pressure fluid containing enclosure thereby substantially increasing the tensile strength of said ring applied to the radial support of said specimen.
